UNITED STATES PATENT OFFICE

154,791

DESIGN FOR A LIGHTING FIXTURE OR THE LIKE

Bernard A. Mitchell, Chicago, Ill.

Application November 6, 1947, Serial No. 142,331

Term of patent 7 years

(Cl. D48—23)

To all whom it may concern:

Be it known that I, Bernard A. Mitchell, a citizen of the United States, residing in Chicago, in the county of Cook and State of Illinois, have invented a new, original, and ornamental Design for a Lighting Fixture or the like, of which the following is a specification, reference being had to the accompanying drawings, forming part thereof.

In the drawings:

Fig. 1 is a perspective view of the lighting fixture showing my new design.

Fig. 2 is a side elevational view thereof, and

Fig. 3 is a reduced bottom plan view thereof.

I claim:

The ornamental design for a lighting fixture, or the like as shown.

BERNARD A. MITCHELL.
